LOUIS COURTOT, OF PARIS, FRANCE.

COOKING STOVE OR RANGE.

1,183,839.

Specification of Letters Patent. Patented May 16, 1916.

Application filed July 22, 1912. Serial No. 710,894.

To all whom it may concern:

Be it known that I, LOUIS COURTOT, a citizen of the Republic of France, residing at Paris, 24 Rue Mogador, in the Republic of France, engineer, have invented certain new and useful Improvements in Cooking Stoves or Ranges, of which the following is a specification.

My invention relates to improvements in cooking stoves or ranges and the same has for its object, more particularly to provide a simple, efficient and reliable furnace in which the fire, which serves to heat the boiler, also serves as the agent for heating the cooking vessel which may be placed upon the top of the stove.

Further said invention has for its object to provide a stove or range having a double walled receptacle provided at its top with an opening through which the hot gases or products of combustion may pass, and then circulate through flues provided between the outer side of said double-walled receptacle or boiler and the inner side of the outer jacket or casing of the stove.

Further said invention has for its object, to provide a stove or range having a double-walled, bell-shaped fluid receptacle, which has its top constructed and arranged to prevent the pocketing of steam, and to prevent the imperfect circulation of the water and thereby eliminate the danger which may result from such imperfect circulation.

Further said invention has for its object to provide a stove or range having a boiler with a separate liquid heating apparatus by means of which a quantity of liquid is diverted and withdrawn from the top of said boiler and passed through the fire space of said stove or range in order to superheat the fluid, and the same then discharged into the fluid outlet leading from the boiler whereby to accelerate the flow or circulation of the main body of fluid through the boiler and its connected parts.

To the attainment of the aforesaid objects and ends my invention consists in the novel details of construction and in the combination, connection and arrangement of parts hereinafter more fully described and then pointed out in the claims.

In the accompanying drawings, forming part of this specification, wherein like numerals of reference indicate like parts:—Figure 1 is a vertical section taken on the

line A A—B B of Fig. 2, showing one form of stove or range constructed according to and embodying my said invention; Fig. 2 is a plan or top view of the same; Fig. 3 is a vertical section taken on the line 3—3 of Fig. 1; Fig. 4 is a transverse section taken on the line 4—4 of Fig. 5 showing a modified construction, and Fig. 5 is a longitudinal section of the construction shown in the transverse section at Fig. 4, the same being taken on the line 5—5 of said figure.

In the accompanying drawings 10 designates the outer casing or shell of a stove which is provided at its front with the usual fire space and ash pit openings 11, 12, respectively, which are provided with doors 11^a, 12^a. The top of the stove is provided with a circular pot-opening 13 within which are fitted the usual concentric rings 14, 15, and a circular cover or lid 16. At the upper rear edge of the casing 10, is provided a smoke pipe or outlet 17.

Within the casing 10 is disposed a bell shaped, double-walled vessel 18 which is rectangular in cross-section and has its front portion vertical and disposed against the inner side of the front of the casing 10. The sides and back of said bell-shaped vessel 18 are inclined upwardly and disposed at a distance from the side and rear walls of the stove casing 10 in order to provide flue spaces whose upper portions are divided by vertical partitions 18^b, 18^c, which extend from the top of the stove casing to a point near the middle of the stove and are provided with vertical openings 18^c controlled by dampers 18^d operated by rods 18^e having their ends extending through the front of the stove casing 10. The upper portion or top of the double walled vessel 18 is inclined downwardly and forwardly and said inclined portion is provided with a rectangular opening 19 which is arranged in line with the pot opening 14 provided in the top of the casing 10. The lower front portion of said double-walled vessel 18 is provided with a rectangular transverse connection 20 which serves to connect the lower opposite sides of said double-walled vessel 18 adjacent to its forward edge.

21 denotes a grate of the usual form which is supported upon lugs 22, 22 secured upon the inner, opposite sides of the double-walled receptacle 18, and below said grate, and on about a level with the upper edge of the transverse member 20, is disposed an ash

pit floor 23, which is supported at its front and rear edges upon lugs 24, 24 extending inwardly from the front and rear walls of said double-walled vessel 18 and the transverse member 20 at the front thereof. The space below said floor 23 is filled with a suitable heat resisting substance 23^a.

25 denotes a pipe, the lower end of which is bifurcated and has said bifurcated ends 10 extending through the top of the stove casing 10 and connected to the upper rear portion of the double-walled vessel or boiler 18. The upper end of said pipe 25 may be connected to a suitable heating apparatus or 15 series of heating apparatus or to any other desired receptacle or container.

25^a denotes a main intake pipe which is connected to the receptacle or boiler 18 at its lower forward portion.

20 26 denotes an accelerator which consists of a plurality of pipes 27, 27 disposed against the inner surface of the rear wall of the double-walled receptacle 18. The upper ends of said pipes 27, 27 are connected 25 together and to an outlet pipe 28 which extends through the top of the double-walled receptacle 18, the top of the stove casing 10, and into the pipe 25 extending from the top of said double-walled receptacle. The lower 30 ends of the pipes 27, 27 extend to a point below the grate 21 and are there brought together and connected to an inlet pipe 29 which extends downwardly through the floor 23 of the ash pit and rearwardly below 35 the rear wall of the double-walled receptacle 18, and thence upwardly behind the outer rear wall of the double-walled receptacle 18, and is connected to said double-walled receptacle adjacent to the top thereof.

40 The operation of the apparatus is as follows:—A part of the water which is initially heated in the double-walled vessel 18 is withdrawn therefrom through the pipe 29 connected to said receptacle adjacent to its upper end, and conducted by said pipe 29 to the pipe sections 27, 27, of the accelerator 26 where the same becomes intensely heated by contact with the heat within the fire space of the stove. As the water becomes 45 superheated or converted into steam, the same is discharged from the end of the pipe 28 and into the main outlet pipe 25 in the same direction as the water flows through said pipe from the double-walled 50 vessel 18. In this way the flow of water within the double-walled vessel 18 is materially accelerated and at the same time the temperature of the water is raised more rapidly and effectively than is otherwise 55 possible.

In order to obtain the most efficient action it is advantageous to supply the accelerator with water which has been previously heated to the highest temperature possible. In order to obtain water at such tem-

perature, the intake pipe of the accelerator is connected to the upper part of the boiler where the water is, of course, hottest. By preference a considerable portion of said intake pipe is arranged in the flue which 70 serves to conduct the hot gases and products of combustion from the combustion chamber of the furnace through the opening 19 in the top of said boiler 18 to the smoke pipe, and the end of said pipe thence carried into the recessed portion of the boiler and connected to the intake portion of the accelerator.

It is to be noted that as the water withdrawn from the upper part of the boiler has 80 already attained a high temperature, it is rapidly superheated or converted into steam while passing through the accelerator, and the pipe 28 leading therefrom, and thereupon issues from the upper end of said pipe 85 28 with considerable velocity, and that the difference in temperature within the flue or flues extending from the combustion chamber to the smoke outlet, within which the intake pipe of the accelerator is located, and 90 that of the combustion chamber itself, in which the accelerator and outlet pipe extending therefrom are located, is sufficient to maintain the desired circulation of fluid in the accelerator and connected parts. 95

At Figs. 4 and 5 a modified form of accelerator is shown. In this construction the accelerator 26^a is shown in the form of a sinuous pipe having its lower end terminating at a point above the grate and connected to an inlet pipe 29^a passing through an opening provided in the rear wall of the double-walled vessel 18^a. The inlet pipe 29^a is then carried upwardly behind the rear wall of the double-walled vessel 18^a and connected 100 thereto adjacent to its top in the same manner that pipe 29 is secured in the main construction above described. The outlet pipe 28^a in this construction also passes through the double-walled vessel 18^a, through the 105 stove casing 10^a, and into the main outlet pipe 25^b extending from the top of the boiler 18^a.

Having thus described my invention, what I claim and desire to secure with Letters Patent is:

1. The combination with a stove and boiler having a main outlet pipe extending therefrom, of an auxiliary heater located within the combustion chamber of said stove, means 120 arranged partly within said boiler and partly between said boiler and the stove casing, connecting one portion of said auxiliary heater with said boiler, and means connecting another portion thereof directly with 125 said main outlet pipe of the boiler, substantially as specified.

2. The combination with a stove and boiler having a main outlet pipe extending therefrom, of an auxiliary heater located 130

- within the combustion chamber of said stove, an inlet pipe arranged partly within said boiler and partly between said boiler and the stove casing and extending from the upper portion of said boiler to the lower portion of said auxiliary heater, and a pipe extending from the upper end of said auxiliary heater to, and opening into said main outlet pipe, substantially as specified.
- 10 3. The combination with a stove and boiler having a main outlet pipe extending therefrom, of an auxiliary heater comprising a plurality of pipes connected together at their adjacent ends, a pipe extending downwardly from the lower connected ends of said auxiliary heater below and to the rear of said boiler and extending upwardly between said boiler and the stove casing and having its end connected to said boiler adjacent to the upper end thereof, and an outlet pipe connected to the upper connected ends of said auxiliary heater and extending into the main outlet pipe extending from said boiler, substantially as specified.
- 20 4. The combination with a stove and boiler having a main outlet pipe extending therefrom, of an auxiliary heater located within and adjacent to the rear wall of the combustion chamber of said stove, a pipe extending from the lower end of said auxiliary heater to a point at the outer side of said boiler and thence upwardly within the flue provided between said boiler and the outer casing of said stove and connected to said boiler adjacent to the upper end thereof, and an outlet pipe extending upwardly from said auxiliary heater and into the main outlet pipe extending from said boiler, substantially as specified.
- 30 5. The combination of a stove, a boiler therein having a recessed central portion, a main outlet pipe extending from said boiler, a grate disposed within the recessed portion of said boiler, and a flue extending from the combustion chamber to the smoke outlet, with an auxiliary heater located within the recessed portion of said boiler adjacent to the inner rear wall thereof and above the grate therein, an inlet pipe extending downwardly from the lower portion of said heater to a point below the base of said boiler and having its end extending upwardly within said flue provided intermediate said boiler and the casing inclosing the same, and having its upper end connected to said boiler adjacent to the upper end thereof, and an outlet pipe extending upwardly from said auxiliary heater and into the main outlet pipe of the boiler whereby to discharge the fluid heated in said auxiliary heater directly into said main outlet pipe in the direction of the flow of fluid from the boiler therethrough, substantially as specified.
- 40 6. The combination of a stove and boiler
- having a main outlet pipe extending therefrom, with an auxiliary heater comprising a plurality of pipes having their adjacent upper and lower ends connected together and disposed within the fire box of said boiler adjacent to the rear wall thereof, an inlet pipe connected to the lower connected ends of said auxiliary heater and extending downwardly below the base of said boiler and thence upwardly to the rear of said boiler and within the stove casing and having its upper end connected to said boiler adjacent to the upper end thereof, and an outlet pipe connected to the upper connected ends of said auxiliary heater and extending upwardly through said boiler and into the main outlet pipe of the boiler, substantially as specified.
- 50 7. The combination of a stove and a boiler having a main outlet pipe extending therefrom, with an auxiliary heater comprising a series of communicating tubes disposed within the fire box of said boiler and above the grate therein, an inlet pipe extending downwardly from said communicating tubes to the rear of said boiler and then extending upwardly between said boiler and the stove casing and having its other end connected to said boiler adjacent to the upper portion thereof, and an outlet pipe extending upwardly from said communicating tubes through the upper portion of said boiler and into the main outlet pipe extending therefrom, substantially as specified.
- 60 8. The combination of a stove and boiler, a main outlet pipe having one end bifurcated and connected to the upper portion of said boiler, and a flue provided intermediate the outer sides of said boiler and the inner sides of the casing surrounding said boiler, with an auxiliary heater comprising a plurality of connected pipes, an inlet pipe connected to the upper rear side of said boiler and extending downwardly therefrom through the flue provided between the outer sides of said boiler and the inner sides of said casing and extending below said boiler and thence upwardly and into the fire box thereof and connected to the lower end of said auxiliary heater, and an outlet pipe secured to the upper end of said auxiliary heater and extending from the top of said boiler into the outlet pipe leading therefrom at the point where said main outlet pipe is connected with its bifurcated ends, substantially as specified.
- 70 9. In a cooking stove the combination of double-walled boiler in the shape of a bell provided at its top with an opening for the issue of gases, and an outlet conduit for the water leading from the top of said boiler, with a tubular, water-circulating device located within the fire box of the stove adjacent to the rear wall thereof; said tubular, water-circulating device having one end ex-

tended outside and upward behind said boiler and opening into the top of said boiler, and having its other end extended upward and opening into said outlet conduit for the water in a direction parallel with said conduit, substantially as specified.

In testimony, that I claim the foregoing

as my invention I have signed my name in presence of two subscribing witnesses.
